UNITED STATES PATENT OFFICE.

RICHARD V. KAIMER, OF NEW HAVEN, CONNECTICUT, AND CHARLES E. RITTER, OF CHICAGO, ILLINOIS, ASSIGNEES TO THE ENGLISH & MERSICK CO., OF NEW HAVEN, CONNECTICUT, A CORPORATION.

LATCH FOR VEHICLE DOORS.

1,415,839.

Specification of Letters Patent.

Patented May 9, 1922.

Application filed May 17, 1921. Serial No. 470,366.

To all whom it may concern:

Be it known that we, RICHARD V. KAIMER, a citizen of the United States, residing at New Haven, in the county of New Haven and State of Connecticut, and CHARLES E. RITTER, a citizen of the United States, residing at Chicago, in the county of Cook and State of Illinois, have invented a new and useful Improvement in Latches for Vehicle Doors; and we do hereby declare the following, when taken in connection with the accompanying drawings and the characters of reference marked thereon, to be a full, clear, and exact description of the same, and which said drawings constitute part of this application, and represent, in—

Fig. 1 an inside face view of a latch for vehicle doors constructed in accordance with our invention.

20 Fig. 2 a front view, partly in section, of the same.

Fig. 3 a view similar to Figure 1, partly in section, showing the bolt in its depressed position and in engagement with the roll-back.

25 Fig. 4 a sectional view on the line 4—4 of Figure 1.

Fig. 5 a sectional view on the line 5—5 of Figure 1.

30 This invention relates to improvement in latches for vehicle doors and particularly to latches which are operated by a vertically-arranged rotary-spindle. The object of the invention is to provide means to positively hold the latch in the thrown position, so that the door may be locked from the inside of the vehicle. In latches operated by a vertically-arranged rotary-spindle it sometimes happens that the latch does not project outward to the limit of its movement and, consequently, the handle on the end of the spindle will not always stand in line with the edge of the door, and another object of this invention is to provide means for holding the handle in proper position, irrespective of the projection of the latch, and the invention consists in the construction and arrangement of parts as hereinafter described and recited in the claims.

40 45 50 In carrying out our invention, we employ the usual case-plate 10, on which is mounted the usual latch 11, with its nose projecting through the flange 13 of the casement. This latch is adapted to be moved by a

cam 14 at the lower end of the vertically-arranged rotatable-spindle 15 which projects up through the edge of the door. The latch is also adapted to be retired by means of the usual roll-back 16, adapted to be turned by a handle from the outside of the door. Generally speaking, the parts thus described are of usual construction.

To provide means for positively locking the latch-bolt in its thrown position, we form the roll-back 16 with a stop-lug 17 to be engaged by a vertically movable bolt 18 extending downward through a suitable housing 19, from an arm 20 which is mounted on the spindle 15, the arm being formed with a cam 21 engaged by a pin 22 mounted in the spindle, so that, when the spindle is turned, the pin 22 will ride over the cam 21 and raise the arm 20, so as to lift the bolt 18 out of engagement with the stop-lug 17. If desired, a spring-bolt 23 may be mounted in the housing 19 to engage with notches 24 or 25 in the edge of the bolt. Around the spindle 15 and resting upon the arm 20 is a sleeve 26, and this sleeve is coupled by a transverse-pin 27 with a push-rod 28 having a push-button 29 which extends upward through a lever-handle 30, which is coupled with the spindle 15 and by which the spindle may be turned. To hold the handle in proper alignment, we mount a spring 31 on the case-plate 10, the end of the spring bearing on the flattened face 32 on the spindle 15. When the handle 30 is turned to retire the nose 12 of the latch-bolt 11, the arm 20 is raised so as to lift the ends of the bolt 18 out of engagement with the roll-back 16, which is then free to be operated by the handle on the outside of the door. When, however, a person desires to lock the car, a downward pressure on the button 29 forces the sleeve 26 downward against the arm 20 and moves the bolt 18 into line with the stop 17 on the roll-back, so that the roll-back cannot be operated from the handle on the outside of the door.

It will be understood that these latches are for use on closed cars, and when leaving the car all the doors except one will be locked from the inside, the door through which the occupant leaves the car being locked in the usual manner from the outside. Thus, all the doors of the car will be securely locked. When, however, the handle 30 of any latch

is turned, the pin 22, operating against the cam 21, will lift the arm 20, and hence retire the bolt 18 out of engagement with the roll-back 16, and the latches are, therefore, 5 free to be operated from the outside. The spring 31, bearing against the spindle 15, will hold the handle 31 in its proper position, irrespective of the position of the latch-bolt.

10 We thus provide a simple means whereby the latch-bolt may be positively locked against operation from the outside. We do not claim broadly means for accomplishing this result, as the broad claim is made the 15 subject of another application filed in even date herewith.

We claim:

1. In a latch for vehicle doors, the combination with a latch-bolt of a vertically-arranged rotatable spindle for moving the same, a roll-back by which the latch-bolt may be moved, said roll-back formed with a stop, a vertically-movable bolt adapted to be projected into the path of said stop, and 25 means operated by the turning of said spindle for lifting said bolt.

2. A latch for vehicle doors comprising a latch-bolt, a vertically-arranged rotatable spindle for moving the same, a roll-back also 30 adapted to move the latch-bolt, said roll-back formed with a stop, an arm mounted on said spindle and formed with a bolt adapted to be projected into the path of said stop, said arm formed with a cam-surface, a pin 35 mounted in the spindle in engagement with

said cam, a sleeve around said spindle and resting on said arm, and a push-pin mounted in the upper end of said spindle and connected with said sleeve, whereby said sleeve may be depressed. 40

3. A latch for vehicle doors comprising a case-plate, a latch-bolt mounted thereon, a vertically-arranged rotatable spindle adapted to move said latch-bolt, a roll-back, also adapted to move said latch-bolt, an arm 45 mounted on said spindle and provided with a bolt adapted to engage with said roll-back, means for lifting said arm by the rotation of said spindle, a sleeve around said spindle and resting upon said arm, a handle applied to the upper end of the said spindle, a push-rod mounted in the upper end of the spindle and provided with a push-button and projecting through the upper face of said handle and coupled with said sleeve. 50

In testimony whereof, I have signed this specification in the presence of two subscribing witnesses.

RICHARD V. KAIMER.

Witnesses:

MARTHA M. THEISS,
RUTH E. BRADLEY.

In testimony whereof, I have signed this specification in the presence of two subscribing witnesses.

CHARLES E. RITTER.
